SAFETY HAT

Luther Paul Barker, Jr., Pacific Palisades, Calif.

Application June 1, 1954, Serial No. 30,764

Term of patent 14 years

(Cl. D3—13)

Fig. 1

Fig. 2

Fig. 3

To all whom it may concern:

Be it known that I, Luther Paul Barker, Jr., a citizen of the United States of America, residing at Pacific Palisades, in the county of Los Angeles and State of California, have invented a new, original, and ornamental Design for a Safety Hat, of which the following is a specification, reference being had to the accompanying drawings, forming a part thereof.

Figure 1 is a front quarter perspective view of a safety hat, showing my new design;

Fig. 2 is a rear quarter perspective view thereof; and

Fig. 3 is a bottom perspective view thereof, showing the interior of the safety hat.

I claim:

The ornamental design for a safety hat, as shown.
